DESIGN FOR A BOTTLE

William Guyer, New York, N. Y., assignor to Joseph E. Seagram & Sons, Inc., Lawrenceburg, Ind., a corporation of Indiana

Application May 24, 1935, Serial No. 57,006

Term of patent 14 years

To all whom it may concern:

Be it known that I, William Guyer, a citizen of the United States, residing at New York, county of New York, and State of New York, have invented a new, original, and ornamental Design for a Bottle, of which the following is a specification, reference being had to the accompanying drawing, forming a part thereof.

Figure 2 is a perspective view showing the bottle and the front and the rear end in perspective.

I claim:

The ornamental design for a bottle as shown.

WILLIAM GUYER.
